(57) **CLAIM**

The ornamental design for a label for an oral care product, as shown and described.

DESCRIPTION

FIG. 1 is a front plan view of a first embodiment of a label for an oral care product showing our new ornamental design; and, FIG. 2 is a front plan view of a second embodiment of a label for an oral care product showing our new ornamental design. The broken line showing of environmental structure in the figures is for illustrative purposes only and forms no part of the claimed design.
